UNITED STATES PATENT OFFICE.

WILLIAM A. RICHEY AND CLEM H. ROWLES, OF AKRON, OHIO.

GASOLINE AND OIL SAVER.

1,421,567.

Specification of Letters Patent. Patented July 4, 1922.

Application filed February 28, 1921. Serial No. 448,668.

To all whom it may concern:

Be it known that we, WILLIAM A. RICHEY and CLEM H. ROWLES, citizens of the United States, residing at Akron, Ohio, have invented certain new and useful Improvements in Gasoline and Oil Savers, of which the following is a specification.

Our invention relates to devices used to connect the breather pipe and intake manifold of automobiles for the purpose of drawing carbureted air from the crank case to the manifold. Among the objects of our invention are: to so simplify the construction of devices of the class indicated as to make them easy to install; to construct a device of the class described in such a manner that it can be readily attached to automobiles of different sizes; to so construct a device of the class indicated that the same can if desired be used to inject inflammable fluid into the manifold intake for starting purposes, and such further objects, advantages and capabilities as will later more fully appear.

Our invention further resides in the combination, construction and arrangement of parts illustrated in the accompanying drawing, and while we have shown therein a preferred embodiment, we desire the same to be understood as illustrative only and not as limiting our invention.

In the drawing annexed hereto and forming a part hereof, Fig. 1 is an elevation of a part of an automobile engine with our improved device attached thereto and Fig. 2 is a fragmentary sectional elevation of the device disassociated from other structure.

Referring more in detail to the annexed drawing, 1 designates the crank case, 2 the carburetor and 3 the manifold intake of an automobile engine. Normally the manifold intake 3 is not provided with an aperture at the point where it branches and it is therefore necessary in applying our device to drill and tap a hole at this point. The screw threaded stopcock 4, attached to one end of a flexible hose 5, may then be screwed into this aperture. To the opposite end of hose 5 is connected a metallic thimble 6 which is secured to the top 7 of a sleeve 8. This sleeve is of such a size that it can be readily slipped into the end of the breather pipe when the cap is removed therefrom. Within the sleeve 8 is secured a piece of fine mesh

wire gauze 9 adapted to prevent any dust or large particles of oil or other foreign matter from passing from the crank case into the manifold intake.

If it is desired to inject benzine, gasoline, or the like into the manifold intake, in order to assist in starting the engine, this can be readily done by withdrawing the sleeve 8 from the breather pipe 10 and holding it with its open end upward. By then pouring a small quantity of the fluid into the open end of the sleeve, the same will be caused to pass through the flexible tube 5 to the stopcock 4, which may then be opened to permit the flow of the fluid into the manifold.

It is of course understood that the specific description of structure set forth above may be departed from without departing from the spirit of our invention as set forth in this specification and the appended claims.

Having now described our invention,

We claim:

1. An automobile accessory comprising a flexible pipe, a stopcock secured to one end thereof and adapted to be screwed into the intake manifold of an automobile, and a substantially cylindrical cap secured to the other end of the pipe and adapted to be used either as a funnel or as a cap for the breather pipe of the automobile.

2. An automobile accessory comprising a flexible pipe, a stopcock secured to one end thereof and adapted to be screwed into the intake manifold of an automobile, and a substantially cylindrical cap secured to the other end of the pipe and adapted to be used either as a funnel or as a cap for the breather pipe of the automobile, said cap having intermediate its ends an enlargement whereby the cap will be prevented from being pushed too far into the breather pipe.

3. An automobile accessory comprising a flexible pipe, a stopcock secured to one end thereof and adapted to be screwed into the intake manifold of an automobile, and a substantially cylindrical cap secured to the other end of the pipe and adapted to be used either as a funnel or as a cap for the breather pipe of the automobile, said cap having intermediate its ends means for filtering fluid passing therethrough so as to prevent foreign substances from getting into the intake manifold.

4. A structure of the character described comprising a tube fitting closely and slidably into the breather pipe of an automobile, a flexible tube opening thereinto, a stopcock 5 secured to the free end of the flexible tube at one end, and having its other end secured to the intake manifold of an engine.

In witness whereof, we hereunto subscribe

our names to this specification in the presence of two witnesses.

WILLIAM A. RICHEY.
CLEM H. ROWLES.
